UNITED STATES PATENT OFFICE.

GEORGE H. RUDISILL, OF SEWICKLEY, PENNSYLVANIA.

FOLDING CRATE OR BOX.

No. 895,793.

Specification of Letters Patent.

Patented Aug. 11, 1908.

Application filed February 7, 1908. Serial No. 414,788.

To all whom it may concern:

Be it known that I, GEORGE H. RUDISILL, a citizen of the United States of America, residing at Sewickley, in the county of Allegheny and State of Pennsylvania, have invented certain new and useful Improvements in Folding Crates or Boxes, of which the following is a specification, reference being had therein to the accompanying drawing.

This invention relates to folding crates and boxes, and the object of this invention is to provide a simple, durable and inexpensive box or crate that can be folded or collapsed to occupy a comparatively small space.

My invention aims to provide a folding box or crate that can be used for numerous purposes, particularly for merchandise of a perishable nature, where the boxes or crates are returned to the original owner for reshipment. In this connection, I have devised a folding or collapsible box or crate that will occupy a comparatively small space when folded, permitting of a large number of boxes or crates to be packed in a freight car for return shipment.

The principle upon which my box or crate is folded or collapsed can be readily applied to numerous other structures, therefore I do not care to confine myself to the specific use of my invention.

The preferred embodiments of my invention are illustrated in the accompanying drawings, wherein

Figure 1 is an elevation of a box or crate in a set up or open position, Fig. 2 is a longitudinal sectional view of the same, Fig. 3 is a longitudinal sectional view of a box or crate in a knocked down or closed position, Fig. 4 is a cross sectional view of a box or crate in a set up or open position, Fig. 5 is a similar view of the box or crate in a knocked down or closed position, Fig. 6 is a perspective view of a portion of the box or crate, Fig. 7 is a plan of a portion of the box or crate in a knocked down or folded position.

To put my invention into practice I provide a plurality of telescopic parts or sections, three being shown in the present illustration, these sections varying in size, whereby one can be fitted or interlocked within the other.

The main frame section which constitutes the outside of the box or crate comprises side boards 1 and 2 and end boards 3, the lower edges of these boards being provided with in-

wardly protruding cleats or flanges 4. The end boards 3 are braced by vertically disposed corner strips 5, and are provided with openings or hand-grips 6, which also serve as keepers, as will be presently described. The second or intermediate frame section fits within the above described frame section and comprises side boards 7 and end boards 8, these boards having their bottom edges provided with inwardly extending cleats or flanges 9 and their upper edges with outwardly extending cleats or flanges 10. The upper cleats or flanges are cut away, as at 11, to clear the vertical strips 5 of the main frame section. The end boards 8 of the intermediate frame section are also braced by vertical corner strips 12.

Fitting in the intermediate frame section is a third section 13, of box-like form, having a bottom 14, and the upper edges of its walls provided with outwardly extending cleats or flanges 15. These flanges or cleats are cut away, as at 16, to clear the vertical corner strips 12 of the intermediate frame.

Hinged as at 17 in the box section 13 are two end locking boards 18, these boards being formed with shoulders 19 and projections 20, the object of which will presently appear.

Adapted to fit upon the box or crate is a lid or cover 21, the ends of said lid or cover being provided with depending angle plates 22 adapted to engage in grooves 23 provided therefor in the end boards 3 of the outer or main frame section of the box or crate. The underneath face of this lid or cover is provided with a dove-tail tongue 24, said tongue engaging in dove-tail grooves 25, 26 and 27 formed respectively in the box section 13, intermediate frame section and outer or main frame section. The tongue 24 is adapted to engage in these grooves and lock said frame sections in a knocked down or folded position, as illustrated in Figs. 3 and 5 of the drawings.

The manner of manipulating my box or crate is as follows:—Assuming that the box or crate is closed or in a knocked down position, as illustrated in Fig. 3 of the drawings, it is only necessary to remove the lid or cover 21 and elevate the outer frame section. As this frame section and the intermediate frame section telescope the box section 13, the outer frame section can be freely moved until the inwardly projecting cleats or flanges 4 engage the outwardly extending cleats or flanges 10 of the intermediate frame section,

at which time this frame section will be carried upwardly with the outer frame section until the inwardly projecting cleats or flanges 9 of said intermediate frame section engage 5 the outwardly projecting cleats or flanges 15 of the box section 13. The box or crate then presents the form illustrated in Fig. 4 of the drawings, and to maintain the frames and box-like structure in this position, the end 10 locking boards are folded upwardly, until the shoulders 19 engage the outwardly projecting cleats or flanges 10 of the intermediate frame section and the projections 20 of said end locking boards engage in the hand-grips or 15 keepers 6 of the outer frame section. These end locking boards 18 brace and maintain the various parts of my box or crate in a fixed position, while the same is being used, or contains merchandise. The lid or cover 21 can 20 then be placed in position to close the box or crate. As the side boards 1 and 2 are formed with grooves to receive the tongue 24, this lid or cover will be held in a closed position by said tongue and angle plates 22. Immediately 25 upon the lid or cover being removed, and the end locking boards 18 folded in the box section 13, the frame sections of the box or crate can be knocked down or collapsed to telescope the box section 13, as illustrated 30 in Fig. 5 of the drawings. To maintain these frame sections in this position, it is essential that the lid or cover 22 be replaced to hold said frames in a closed and locked position. When in a knocked down or folded 35 position, the box or crate presents a strong, compact and durable structure that will occupy a comparatively small space, particularly when being transported in freight cars.

My folding box or crate can be constructed 40 of wood, metal or a material capable of withstanding the rough usage to which shipping boxes or crates are subjected.

I reserve the right to make such changes in my invention as are permissible by the appended claims.

Having now described my invention what I claim as new, is:—

1. A folding box comprising a main flanged

frame section, an intermediate flanged frame section telescoped by said main frame section, a box section having flanges engaged by said intermediate frame section and telescoped thereby, end locking boards hinged in said box section and adapted to engage said intermediate and main frame sections for 55 maintaining the same in a set up position, a lid or cover adapted to fit upon said main frame section, depending angle plates carried thereby for engaging in the end boards of said main frame section, and a dove-tail 60 tongue carried by said lid or cover for engaging all of said sections and securing them in a telescoped position.

2. A folding box comprising telescopic main and intermediate frame sections, a box 65 section telescoped by said main and intermediate frame sections, hinged end locking boards carried by said box section for maintaining said main and intermediate frame sections in a set up position, a lid or cover 70 adapted to fit upon the main frame section, and a dove-tail tongue carried by said lid or cover for locking said main and intermediate frame sections in engagement with said box section.

3. A folding box, comprising a box section and a plurality of telescoping frame sections, flanges carried by each of said sections to limit their movement in one direction, locking members hinged to the box section to 80 fold inwardly therein and having lugs adapted, when said members are in the extended position to engage in openings provided therefor in the uppermost frame section and hold said sections in the extended portion, a 85 lid or cover engaging the uppermost frame section, and means carried by said lid or cover for engagement with each of the sections when the latter are telescoped to lock them in telescoped position.

In testimony whereof I affix my signature in the presence of two witnesses.

GEORGE H. RUDISILL.
